UNITED STATES PATENT OFFICE.

EDWIN J. YOUNG, OF WADSWORTH, OHIO, ASSIGNOR TO THE OHIO
INJECTOR COMPANY, OF SAME PLACE.

INJECTOR.

SPECIFICATION forming part of Letters Patent No. 579,212, dated March 23, 1897.

Application filed July 11, 1896. Serial No. 598,878. (Model.)

To all whom it may concern:

Be it known that I, EDWIN J. YOUNG, a citizen of the United States, residing at Wadsworth, in the county of Medina and State of Ohio, have invented a certain new and useful Improvement in Injectors, of which the following is a full, clear, and exact description.

The object of this invention is to provide in one structure the three valves which are used for the inlet of the steam to an injector, to the lifting-tube, and to the forcing-tube, and to operate the said three valves conjointly or successively by a single operating device.

In the selected illustration of my invention I have shown a double-tube injector, one of the tubes being the injector proper and the other tube being the ejector or lifter, to raise the water from a well or other source of supply to the injector, whence it is forced to the boiler. The injector comprises a steam inlet and chamber, a steam-nozzle and forcing-tube, an overflow, and a boiler connection, which may be substantially as usual, excepting that a chamber is interposed between the overflow and ejector and contains an automatic valve of this invention, and between the inlet and the steam-nozzle is interposed the triple valve of this invention, one portion of the valve serving to control the admission of steam to the injector and ejector, another portion of the valve coöperating with the first-named portion to control the admission of steam to the steam-nozzle and forcing-tube, and the third portion of the valve serving to cut off the supply of steam from the ejector, this triple valve having a common moving device, all as I will proceed now more particularly to set forth and finally claim.

In the accompanying drawings, illustrating my invention, in the several figures of which like parts are similarly designated, Figure 1 is a longitudinal section of the complete apparatus with the parts shown as closed. Fig. 2 is a longitudinal section of a portion of the injector with the valves in position to admit steam to the ejector. Fig. 3 is a longitudinal section of a portion of the injector with the valves open, to admit steam both to the ejector and to the injector and its steam-nozzle and forcing-tube. Fig. 4 is a longitudinal section showing the triple valve in position to cut off

the steam entirely from the ejector. Fig. 5 is a sectional elevation of the casing.

The casing *a* of the injector may be made in any usual manner and be supplied with a steam-inlet nipple *a'*, an overflow *a²*, and a boiler connection *a³*, and also with a steam-nozzle *a⁴* and a forcing-tube *a⁵*, all substantially as usual, excepting that the forcing-tube is provided with spilling-ports *a⁶*. The overflow is provided with a cap *b*, which also serves as a guide for the stem of the overflow-valve *b'*.

c is a tube supplied with a nipple *c'* for connection with a water-supply, and the tube *c* contains the steam-nozzle *c²* and the lifting-tube *c³*, access to which is had by means of the removable cap *c⁴*, which cap also serves to close the steam-chamber *c⁵*. Within the injector-tube is the steam-chamber *d*, which is closed by the cap *d'*. A second steam-chamber *e* is provided in the injector-tube, and the said chambers *d* and *e* are separated one from the other by means of the valve-seat *f* and the triple valve hereinafter described. A port *g* connects the steam-chamber *e* of the injector and the steam-chamber *c⁵* of the ejector, and the said ejector is further connected with the injector by means of a duct *h*, which opens from the injector into a chamber *h'* in the injector adjacent to the overflow and containing the automatic valve *b'*. This valve *b'* is arranged immediately between said chamber and the overflow and controls communication between the injector, chamber, and overflow, and thus renders the double-tube injector automatic in its action.

The triple valve comprises a tube *i*, having the valve portion *j*, which coöperates with the valve-seat *f*, and beyond the valve *j* the said tubular portion *i* is provided with the ports or openings *k*. The portion *i* is provided also with the valve-face *l*, which coöperates with the inlet *g'* of the port *g*, the said valve-face *l* traveling upon guides *l'* in the injector-tube *a*. The farther end of the tubular portion *i* is partly closed by an annulus or flange *m*. Within the tubular portion *i* is arranged the independently-movable valve *n*, which has a pointed end projecting beyond the tubular portion *i* and adapted to coöperate with the steam-nozzle *a⁴* as a valve-

seat, the said valve *n* having the shoulder *n'* back of its projecting portion to coöperate with the annulus or flange *m*.

o is a valve-stem threaded, as shown, to coöperate with a complementary thread in the cap *d'* and secured steam-tight in said cap by any suitable gland *p*, the said stem *o* having an operating-handle *q* outside of the injector-tube. This stem *o* has a head *r*, which is fitted to a cavity in the tubular portion *i*, and is secured therein with a capacity, if desired, of rotation by means of a nut *s*.

The tubular portion *i*, with its two valves *j* and *l*, and the valve *n* constitute what I have herein designated a "triple valve," and its functions, as already indicated and as will presently more fully appear, are to admit steam to the ejector alone and also and simultaneously to the ejector and the injector and to cut off steam from the ejector.

The operation is as follows: When the triple valve has been moved by the rotation of the spindle *o* sufficiently to clear the valve *j* from its seat *f*, steam will be admitted into the steam-chamber *e* and will pass into the port *g* and into the ejector, and at the same time the steam within the valve portion *i* will serve to hold the valve *n* to its seat, and thus exclude steam from the steam-nozzle *a'* and consequently the forcing-tube *a''*. As soon as the flow of water is established and appears at the overflow by lifting the valve *b'* a further movement is imparted to the triple valve by the rotation of the stem *o* until the annulus or flange *m* engages the shoulder *n'* of the valve *n* and forces said valve from its seat in the steam-nozzle *a'*. Steam then will be admitted simultaneously to the injector and the ejector, and the water will be forced into the boiler. The triple valve then is given a further movement in the same direction until the valve *l* is moved partly or wholly over the port *g*, thereby still admitting steam to the injector, but cutting off part or all of the steam from the ejector and consequently reducing the delivery of water from the ejector to the quantity the force can deliver to the boiler, or, if desired, to a much smaller quantity, thereby grading the injector to its least capacity. Moreover, when water is supplied from city mains or other sources under pressure the valve *l* may be used to cut off all the steam from the ejector.

Thus it will be seen that the three valves are operated and controlled by a single device—namely, the stem *o* and its handle.

It is to be observed that my apparatus is perfectly automatic in action, as much so as any single-tube automatic injector.

6. If for any reason the jet should be momentarily broken after the injector is once started, the force will exhaust steam out through the overflow until the injector again lifts water, at which time the force takes it and again establishes the jet to the boiler without any movement of the steam-valve by the operator.

It is to be observed, further, that there is

nothing between the ejector and the overflow, excepting the automatic valve *b'*, and that the water must pass the force on its way to the overflow-valve through chamber *h'*.

My apparatus is what may be designated a "self-contained injector," requiring no valves in the steam and suction pipes, and is wholly controlled by the one operating device. It will work on an extreme lift, or by cutting off the steam to the ejector it will work as a non-lifting injector and will work automatically under all conditions.

What I claim is—

1. A triple valve for double-tube injectors, comprising a main steam-valve for controlling the admission of steam to both tubes, and a separate steam-valve under the main valve and operating automatically and independently of the main valve under steam-pressure and also conjointly and positively with the main valve, for controlling the admission of steam to the force, substantially as described.

2. In a double-tube injector, the main steam-valve provided with a separate valve closed automatically by steam-pressure for coöperation with the steam-inlet to the injector-tube, substantially as described.

3. In a double-tube injector, a triple valve comprising a main steam-valve, a separate steam-valve working automatically and also conjointly with the main valve for controlling the steam to the force, and an injector-valve, and an operating device common to all, substantially as described.

4. In a double-tube injector, an injector-tube provided with a steam-chamber between the steam-inlet and the steam-nozzle, a port connecting the said steam-chamber with the injector-tube, a main valve interposed between the steam-inlet and the said steam-chamber, and a graduating-valve connected with the main valve, as set forth, so that the graduating-valve closes the port to the injector upon movement of the main valve, and again opens said port by forward movement of the main valve and before the main valve cuts off steam, substantially as described.

5. In a double-tube injector, a chamber interposed between the injector and the overflow, and an automatic valve interposed immediately between and controlling communication from the said injector and chamber to the said overflow, substantially as described.

6. In a double-tube injector, a chamber interposed between the injector and the overflow, an automatic valve interposed immediately between said chamber and the overflow and controlling communication from the injector and chamber to the overflow, and a triple valve for controlling the admission of steam to the two tubes, substantially as described.

7. In a double-tube injector, a chamber arranged between the injector and the overflow, an automatic valve interposed immediately between the said chamber and overflow and controlling communication from the said

ejector and chamber to the overflow, a forcing-tube arranged in said chamber and containing spilling-ports, and a steam-controlling valve, substantially as described.

5 8. In an injector provided with a water-raising contrivance and a combining and forcing tube, a triple valve interposed between these devices and the steam-inlet, and controlling the admission of steam to both, and comprising a tubular portion having a valve seated immediately in the steam-inlet, and having a separate valve-face for independently controlling the admission of steam to the water-raising contrivance, and a third 15 valve arranged within those first named, and at one time seated by steam-pressure independently of the movements of the other valves, and at another time unseated by the further movement of the said first-named 20 valves, and a valve-moving device common to the said three valves, substantially as described.

9. In an injector, the steam-inlet having a valve-seat, a steam-nozzle also having a valve-seat, a water-lifting tube having a valve-seat, 25

and a triple valve having separate valve-faces for said several seats and operated successively by an operating device common to all, substantially as described.

10. In an injector having a steam-inlet and 30 a valve-seat therein, a steam-nozzle and a valve-seat therein, and a lifting device in open communication with the injector between the inlet and the steam-nozzle, and a triple valve having a valve-face coöperating 35 with the valve-seat in the inlet, a valve actuated successively by pressure of steam and by forcible contact with the valve of the steam-inlet, a valve-face for controlling the communication with the water-lifting device 40 and independent steam-supplying passages arranged between the inlet steam-valve and the last-named valve, substantially as described.

In testimony whereof I have hereunto set 45 my hand this 6th day of July, A. D. 1896.

EDWIN J. YOUNG.
